UNITED STATES PATENT OFFICE.

LINDEN A. THATCHER, OF BELLEVILLE, NEW JERSEY, ASSIGNEE TO UNDERWOOD TYPEWRITER COMPANY, OF NEW YORK, N. Y., A CORPORATION OF DELAWARE.

STENCILING MACHINE.

Application filed September 24, 1924. Serial No. 739,473.

This invention relates generally to stencil machines, and more particularly to means for distributing or spreading ink around the inner periphery of the stencil cylinder.

One of the features of the invention involves placing the ink fountain entirely outside of the stencil cylinder so that it may be readily filled, cleaned or inspected, provision being made for the flow of ink from the fountain to the bristles of a distributing brush interior of the stencil cylinder, and by means of which it may then be spread upon the cylinder wall.

Another feature is the provision of means for mounting the distributing brush within the cylinder, so that it may be either removed bodily as a unit from the machine, when out of use, or swung to a position so as to remove the bristles from contact with the wall of the cylinder, and secured in such position during the ordinary operation of the machine.

Another feature of the present invention is the provision of a brush carrier or housing such that the brush proper may be readily removed from said housing for cleaning purposes.

A further feature is the provision of a stencil cylinder which may be readily and quickly removed from the machine without the necessity of removing or disturbing certain parts of the ink feeding mechanism.

Other features and advantages will hereinafter appear.

In the accompanying drawings,

Figure 1 is a longitudinal section through a conventional stenciling machine showing the ink distributor and ink reservoir in position thereon.

Figure 2 is a view of the ink distributing brush and its associated parts.

Figure 3 is a group view showing the ink brush and its carrier spread out, and in the order of their assembly.

Figures 4, 5 and 6 are detail views of the distributing brush and the brush carrier.

Figure 7 is a perspective view of the brush carrier or housing with portions

broken away so as to show the interior construction thereof.

Figure 8 is a transverse section on the line 8—8 of Figure 1.

Figure 9 is a section on the line 9—9 of Figure 8.

Figure 10 is a section on the line 10—10 of Figure 1 and shows certain details of the distributing mechanism.

Figure 11 is a detail view of one of the end spiders of the stencil cylinder and taken on the line 11—11 of Figure 1.

For illustrative purposes, I have shown in the accompanying drawings, my ink distributing device applied to a conventional form of stencil machine in which a perforated hollow cylinder or drum is covered with an ink blanket, the paper to be stenciled being run between a stencil-sheet and a pressure roll, the ink being applied to the interior of the cylinder and taken up by an ink blanket upon the exterior wall thereof. A machine of this character is disclosed in the application of Edward G. Rowley, Serial No. 721,982, filed June 24, 1924.

Referring to the drawings, and with particularity to Figures 1 and 8 thereof, 10 designates a frame, which includes end standards 11 and 12. The upper portion of the standard 11 is formed with a collar 13, the barrel 13' of which receives and provides a mounting for a stationary central shaft 14, which extends horizontally throughout the length of the stencil cylinder 15 of the machine, the shaft being secured within the collar by any suitable means such as a set screw 14'. An ink blanket *b* is wrapped about the cylinder 15, the end of the blanket being secured within the usual channel *c* formed in the cylinder wall by means well known in the art. One end of the cylinder 15 is provided with a spider 16, having a central hub 17, mounted to revolve upon the shaft 14, and the cylinder is secured against lateral movement by means of a latch 18 pivotally mounted at 19 upon the upper end of the standard 11 and having a finger 20 held into engagement with an an-

nular groove 21 in the hub 17, by means of a suitable spring 22 acting against the under side of a finger-piece 23 of the latch 18. The outer end of the cylinder may be 5 mounted to revolve upon roller 24 carried by a yoke-shaped member 25 of the frame, in the usual manner, and a handle 26 provides means whereby the cylinder may be rotated. An annular flange 15' extends around the 10 inner wall of the cylinder 15 adjacent the outer end thereof. A sleeve 27 is mounted for telescoping movement upon the shaft 14 and is provided, at a point approximately intermediate its ends, with a yoke-shaped 15 bracket 28, encircling the sleeve 27 and having a pair of oppositely-disposed ears 29 between which a lever 30 is pivoted upon a threaded pin 31 secured by a suitable lock-nut 32.

20 It will be noted that the lever 30 has two arms, one arm 33 of which extends toward the spider 16 and terminates in lugs 34 and 35 which are directed outwardly from the body of the lever 30 and then bent at right angles and secured to the inner side walls 36 of a housing or brush carrier 37 by means of rivets 36', or in any other manner found desirable. As clearly illustrated in Figures 1 and 2, the brush carrier is substantially 25 rectangular in plan and comprises a box-like structure including a top wall 38, having an elongated perforation 39 therein, the purpose of which will appear later in the description. L-shaped members 40, extend 30 across the interior of the carrier 37, adjacent the ends thereof, and cleats 41 are spaced from and underlie the members 40 so as to provide guideways for receiving the head 42 of a brush 43 provided with bristles 44. Thus, it will be noted that a trough 42' is formed by the top of the head 42 of the brush and the side walls of the brush carrier extending thereabove. A gate 45 is arranged to drop into a slot 46 provided adjacent the outer end of the brush carrier in the top wall 38 behind the adjacent end of the brush head 42, when said brush is within the carrier. The gate may be slightly 45 wedge-shaped in cross section so as to become tightly wedged in the slot 46 and thereby retain itself in place. The head 42 of the brush 43 is cut away or notched out as at 47 to provide a pair of channels adjacent the interior side walls 36 of the brush carrier 37, and the lower side walls of the carrier are 50 inclined downwardly and inwardly as indicated at 48, so that the lower edges thereof are in contact with the sides of the bristles 44. A perforation 49 through the head 42 communicates with the bristles. A pair of outstanding ears 37' carried upon the inner end of the brush carrier 37 act as a stop against the annular flange 15' to limit the 55 outward movement of the brush 43 and also as a stop to prevent the brush or carrier

from becoming injured against the sides of the channel *c* when the ink distributor is moved about within the cylinder, in a manner later described. The brush may be quickly removed for cleaning or for substituting a new one simply by removing the gate 45 and sliding the brush outwardly toward the open end of the brush carrier as will be readily understood.

The other arm 50 of the lever 30 extends 75 toward the outer end of the stencil cylinder and is characterized by a right-angular portion 51 bent to provide finger-pieces 52 and 53, respectively, overlying and underlying the sleeve 27, the latter carrying a perforated ear 54 upon one side thereof, and a tension spring 55, attached at one end to said ear 54 and at the other end to a perforation in the finger-piece 53, normally causes the lever to be rotated about its pivot pin 80 31 to press the bristles 44 against the inner wall of the stencil cylinder. A detent or latch 56 carried by the sleeve 27 is formed with a hooked end 57 to engage the under edge of the arm 33 upon pressure applied to 85 the finger-piece 52 to move the brush carrier 37 to the position indicated in dotted lines at 58 in Figure 1. A stop lug 59 carried upon the upper edge of the arm 33 engages against the under side of the sleeve 27, 90 and thereby limits the throw of the brush carrier 37 to the position shown in dotted lines mentioned above. A knob 60 is secured to the outer end of the sleeve 27 and provides means whereby motion may be imparted to the brush for the purpose of distributing ink around the interior wall of the cylinder.

Upon the standard 11 there is secured, 105 by means of suitable screws, a vertically-disposed bracket 62, the upper end of which is directed at right angles to provide a shelf 63 upon which an ink container or reservoir 64 is fastened by means of a screw 65. The reservoir has communication to the interior 110 of the stencil cylinder through a piston cylinder 66 contained within the reservoir 64, thence through a tubular channel or duct 67 formed in the adjacent end of the stationary shaft 14, and then through a spout 68 which is disposed downwardly and at right angles from the channel or duct 67, as clearly illustrated in Figure 1. A cover 69 is secured to the upper end of the reservoir 64 by any suitable means such as screws 115 70, and it will be noted that the cover is provided with a filler cap 71 and a depending boss 72 having a vertical bore 73 arranged to receive a piston rod 74. A piston 75 carried by the lower end of the rod 74 fits within the piston cylinder 66 and the upper end of the rod carries a button 76. A pocket 77 formed in the boss 72 provides a space around the upper portion of the rod 74, and a tension spring encircling the rod 120 125 130

acts against the under surface of the button 76 and the floor of the pocket 77 to cause said piston to move toward the open end of the cylinder. A pin 74' passing 5 through the rod 74 engages the lower portion of the boss 72 to limit the upward movement of the piston to the position indicated in full lines in Figures 1 and 8. An opening or slit 78 formed in the wall of the piston 10 ton cylinder 66 and communicating with the interior of the reservoir 64 permits ink to flow from the container into the piston cylinder and thence to the duct 67.

In order to permit the stencil cylinder to 15 be removed from the machine, the hub 17 and the spider 16 are cut out as at 79, so that after the sleeve 27 and its associated parts have been removed and the latch 18 operated to cause the finger 20 to become 20 disengaged from the annular groove 21, the stencil cylinder may be moved laterally along the shaft 14 toward the outer end thereof and the cut-out portions above mentioned provide sufficient clearance around 25 the spout 68 to permit the spider 16 and the hub 17 to pass over the spout without interference therewith.

In operation, the cap 71 is removed and the reservoir 64 filled with ink, after which 30 the knob 60 is grasped and the brush carrier moved to the position indicated in full lines in Figure 1, that is, to place the trough 42' vertically beneath the spout 68. In the meantime, the ink has flowed through the 35 slit 78 in the cylinder 66 and into the duct 67, the heavy consistency of the ink preventing it from flowing through the spout until forced. The button 76 is then depressed to drive the piston 75 downwardly, 40 thus causing the ink contained within the cylinder 66 and duct 67 to be projected from the spout 68 and into the trough 42' of the brush carrier 37. The ink then spreads over the head 42 of the brush 43 and downwardly through the channels formed by the 45 side walls 36 and the notched-out portions 47 of the brush head, and is then directed to the bristles 44 through the medium of the downwardly and inwardly inclined 50 side walls 48 of the brush carrier 37. Some of the ink may find its way to the interior of the brush through the perforation 49. Now, the knob 60 may be moved back and forth and turned axially in one direction 55 and then in the other so as to cause the bristles 44 to reach all parts of the interior surface of the stencil cylinder, thus covering the same with a uniform and well distributed coating of ink.

60 When out of use the whole brush structure, including the brush 43, the brush carrier 37, the lever 30, the sleeve 27 and the knob 60, may be readily removed, as a unit, from the stencil cylinder by simply 65 shifting the brush to its inoperative posi-

tion and then moving the knob away from the outer end of the machine until the sleeve 27 is withdrawn from the shaft 14.

Due to the simplified construction of the ink reservoir and its position exterior of 70 the stencil cylinder, the parts are easily accessible for cleaning or inspection and the reservoir may be readily filled with ink.

Variations may be resorted to within the scope of the invention, and portions of 75 the improvements may be used without others.

Having thus described my invention, I claim:

1. In a stenciling machine, the combination with a stencil cylinder, of a hollow shaft extending through the cylinder and on which it rotates, an ink reservoir fast to said shaft and in connection with the interior thereof, an ink feeding spout communicating from said shaft to the interior of the cylinder, pressure means for causing ink to flow from the reservoir through said spout, and an ink distributing device including a sleeve mounted for telescoping 80 and rotary movement upon the shaft, said device including a brush carrying arm pivoted upon said sleeve, a brush housing carried upon the free end of said arm, a brush including a head having openings 85 thereon and bristles, said head being secured within the housing and having an ink-pocket formed thereabove, whereby to receive ink from said spout and permit said 90 ink to flow downwardly through said openings and onto the bristles.

2. In a stenciling machine, the combination with a stencil cylinder, of a hollow spindle extending through the cylinder and on which it rotates, an ink reservoir fast 105 to said spindle and in connection with the interior thereof, an ink feeding spout communicating from said spindle to the interior of the cylinder, means for causing ink to flow from said reservoir and through the 110 spout, a sleeve mounted for telescoping and rotary movement upon said spindle, and a lever pivoted upon the sleeve, said lever including a brush carrying arm and a spring 115 actuated arm, said spring actuated arm being effective to move said brush carrying arm toward the inner wall of the cylinder.

3. In a stenciling machine, in combination, a stencil cylinder, a hollow shaft 120 through the cylinder and on which it rotates, an ink reservoir fast to said shaft and connecting with the interior thereof, an ink feeding spout communicating from said shaft to the interior of the cylinder, means for feeding ink through the spout, an ink 125 distributing device comprising a sleeve mounted for telescoping and rotary movement upon said shaft, a lever pivoted upon the sleeve, said lever including a brush carrying arm and a spring actuated arm for 130

moving said brush carrying arm toward the inner wall of the cylinder, and means for holding said brush carrying arm away from the wall of the cylinder against the action of said spring actuated arm, when the ink distributing device is out of use.

4. In a stenciling machine, in combination, a stencil cylinder, a hollow shaft extending through the cylinder and on which it rotates, an ink reservoir fast to said shaft and connecting with the interior thereof, an ink feeding nozzle having communication from said shaft to the interior of the cylinder, means for forcing ink from the reservoir and through said nozzle, an ink distributing device comprising a sleeve mounted for telescoping and rotary movement upon said shaft, a lever pivoted upon the sleeve, said lever including an arm arranged to be swung toward the inner wall of the cylinder, a housing fixed to the free end of said arm, and a brush received in said housing and including bristles and a head having portions thereof cut away to provide passageways adjacent the inner side walls of said housing, the lower side walls of said housing being inclined downwardly and inwardly to engage the adjacent sides of the bristles, the upper portion of said housing extending above the head of the brush to provide a trough therearound, so that ink received in said trough from the nozzle flows downwardly through said passageways and thence over said inclined walls and onto the bristles.

5. In a stenciling machine, in combination, a stencil cylinder, an annular flange around the interior of said cylinder adjacent the outer end thereof, a hollow shaft extending through the cylinder and on which it rotates, an ink reservoir fast to said shaft and connecting with the interior thereof, an ink feeding spout having communication from said shaft to the interior of the cylinder, means for forcing ink from the reservoir and through said spout, an ink distributing device comprising a sleeve mounted for telescoping and rotary movement upon said shaft, a lever pivoted upon the sleeve, said lever including an arm arranged to swing toward the inner wall of the cylinder, a housing fixed to the free end of said arm, a brush received in said housing and including bristles and a head having portions thereof cut away to provide passageways adjacent the inner side walls of said housing, the lower side walls of said housing being inclined downwardly and inwardly to engage the adjacent sides of the bristles, the upper portion of said housing extending above the head of the brush so as to provide a trough therearound, and a pair of outwardly directed ears carried by said housing, so that, when said ink distributor is rotated adjacent the outer end of the

cylinder, said ears engage said annular flange to limit the outward movement of the brush.

6. In a stenciling machine, in combination, a stencil cylinder, a shaft extending through the cylinder and on which it rotates, a sleeve telescoping on said shaft, a lever pivoted to said sleeve and including a pair of oppositely-directed arms, a brush carrying housing fixed to the free end of one of said arms, and spring means associated with the free end of the other of said arms, so as to cause said brush carrying housing to hold its brush in yielding engagement with the inner wall of said cylinder during an inking operation.

7. In a stenciling machine, in combination, a stencil cylinder, a shaft extending through the cylinder and on which it rotates, a sleeve telescoping on said shaft and movable longitudinally and angularly thereabout, a bracket on said sleeve, a lever pivoted to said bracket and including a pair of oppositely-directed arms, a brush carrying housing fixed to the free end of one of said arms, spring means associated with the free end of the other of said arms, so as to cause said brush carrying housing to hold its brush in yielding engagement with the inner wall of said cylinder during an inking operation, and a detent for holding said first-mentioned arm away from said wall when the inking operation is completed.

8. In a stenciling machine, the combination with a stencil drum, of an ink-distributor movable within the drum and including a pivoted arm, a housing fixed to the free end of said arm, a brush slidably received in said housing, means for retaining said brush in position within said housing, and means for operating said arm, so as to cause the brush to move about the interior of the drum in contact with the surface thereof.

9. In a stenciling machine, the combination with a stencil drum, of an ink-distributor movable within said drum and including a pivoted arm, a housing fixed to the free end of said arm, runways extending within the interior of said housing, a brush received upon said runways, means for securing said brush in position within the housing, and means for operating said arm so as to move said brush about the interior of the drum in contact with the wall thereof.

10. In a stenciling machine, the combination with a stencil drum, of an ink-distributor movable within said drum, said distributor including a box-like housing, a pair of oppositely-disposed side walls depending from said housing, runways carried by said side walls upon the inner faces thereof, a brush-head received by said runways and including bristles projecting beyond the lower edges of said depending side walls,

means engaging the head of said brush to retain the same within said housing, and means for moving said distributor about the interior of the drum so as to cause the brush to reach all the parts of the useful surface thereof.

11. In a stenciling machine, the combination with a stencil drum, of an ink-distributor movable within said drum, said distributor including a box-like housing, a pair of oppositely-disposed side walls depending from said housing and inclined inwardly and downwardly, runways carried upon the inner faces of said side walls, a brush-head received by said runways and including bristles projecting beyond the lower edges of said depending side walls and in contact with the inclined portions thereof, and a latch-piece carried by said housing and positioned behind one end of said brush-head to retain the brush within the housing.

12. In a stenciling machine, the combination with a stencil drum, of an ink-distributor movable within said drum, said distributor including a box-like housing, a pair of oppositely-disposed side walls depending from said housing and inclined inwardly and downwardly, runways carried upon the inner faces of said side walls, a brush-head received by said runways and including bristles projecting beyond the lower edges of said depending side walls and in contact with the inclined portions thereof, said brush-head having its side edges cut away to provide passageways with the adjacent inner walls of the housing, and means for securing said brush within the housing.

13. In a stenciling machine, the combination with a stencil drum, of an ink-distributor movable within said drum, said distributor including a box-like housing, a pair of oppositely-disposed side walls depending from said housing and inclined inwardly and downwardly, runways carried upon the inner faces of said side walls, a brush-head received by said runways and including bristles projecting beyond the lower edges of said depending side walls and in contact with the inclined portions thereof, said brush-head having edges cut away to provide passageways with the adjacent inner walls of the housing, said housing also having a slot adjacent the outer edge thereof and extending parallel therewith between the side walls, and a gate arranged to be received in said slot to retain said brush within the housing.

14. In a stenciling machine, in combination, a rotatable drum, a hollow shaft extending through the drum and on which it rotates, said shaft having an opening therein communicating with the interior of said drum, an ink reservoir fixed to said shaft exterior of the drum, a cylinder within the reservoir, a piston within said cylinder, and an

operating handle extending from the piston to the exterior of the reservoir, whereby said piston may be operated to cause ink to flow from the reservoir and through said opening of the hollow shaft.

70

15. In a stenciling machine, in combination, a rotatable drum, a hollow shaft extending through the drum and on which it rotates, said shaft having an opening therein connecting with the interior of said drum, an ink reservoir fixed to said shaft and supported exteriorly of said drum, a relatively minute cylinder within the reservoir and having a port in the side wall thereof and communicating with said reservoir, a pumping piston within the cylinder, and an operating rod extending from the piston to the exterior of the reservoir, so that a relative minute quantity of ink flowing from said reservoir and into said cylinder is expelled from said opening of the hollow shaft upon full operation of said rod.

80

85

90

95

100

16. In a stenciling machine, in combination, a rotatable drum, a hollow shaft extending through the drum and on which it rotates, said shaft having a spout communicating from said hollow shaft to the interior of the drum, an ink reservoir fixed to the shaft and exterior of the drum, a cylinder within the reservoir and having the side wall thereof cut away to provide a port communicating from said cylinder to the interior of the reservoir, a piston within said cylinder, an operating rod extending from the piston to the exterior of the cylinder, and resilient means for normally holding said piston in such position as to permit ink to flow through the port and into said cylinder.

17. In a stenciling machine, in combination, a rotatable drum, a hollow shaft extending through the drum and on which it rotates, said shaft having an ink spout communicating from said hollow shaft to the interior of the drum, an ink reservoir fixed to the shaft and exterior of the drum, a cylinder within the reservoir, said cylinder having the side wall thereof cut away to provide a port communicating from said cylinder to the interior of the reservoir, a piston within the cylinder and capable of covering said port when moved inwardly of the cylinder, an operating rod extending from the piston to the exterior of the reservoir, resilient means for moving said piston toward the outer end of the cylinder so as to uncover the port, and stop means for arresting such movement so as to limit the degree of opening of said port.

110

115

120

125

18. In a stenciling machine, in combination, a shaft having a passageway therein, an ink feeding spout projecting from the side thereof, a stencil drum, and a spider, a hub forming a part of said drum and mounted to revolve upon the shaft, said spider and hub having portions thereof cut away adja-

130

cent said shaft so as to provide sufficient clearance around said spout to permit said cylinder to be moved from the machine longitudinally of the shaft.

5 19. In a stenciling machine, in combination, a hollow shaft, an ink-feeding spout projecting from the side thereof, a stencil drum, and a spider including a hub forming

a part of said drum and mounted to revolve upon the shaft, said spider having an elongated perforation therein and said hub cut away so as to provide sufficient clearance to permit said spider and hub to clear the spout, when the drum is moved longitudinally of the shaft.

LINDEN A. THATCHER.
